MATTRESS

Peter C. Bednarek, Chicago, Ill., assignor to
Ostermoor & Company, Bridgeport, Conn., a
corporation of New York

Application January 22, 1940, Serial No. 314,925

4 Claims. (Cl. 5—356)

The invention relates to the manufacture and construction of mattresses.

Heretofore, it has been the usual practice to tuft mattresses by extending ties through both the top and bottom paddings and covering and through the core and securing tufts or buttons to the ends of the ties.

One object of the invention is to provide a method of securing the top and bottom coverings to the spring center core, and a mattress construction in which the top and bottom coverings are separately tufted without the use of ties between the top and bottom of the mattress.

Another object of the invention is to provide a method and means whereby the assembling of preformed top and bottom coverings can be expeditiously secured to, and assembled with, the spring structure or core of the mattress.

Another object of the invention is to provide fasteners which are adapted to extend through, and be secured to, the separate padded coverings, and which include means for clipping or snapping their inner ends to the spring center core of the mattress.

These objects are attained by the use of fasteners which are adapted to, and are, passed through the coverings and compress the filling at spaced points before assembly with the spring center core and providing the fastener with hooks or clips for attaching the fasteners to the core.

Other objects of the invention will appear from the detailed description.

The invention consists in the several novel features which are hereinafter set forth and are more particularly defined by claims at the conclusion hereof.

In the drawing: Fig. 1 is a vertical section of a portion of a mattress embodying the invention and being assembled in accordance therewith. Fig. 2 is a section on line 2—2 of Fig. 3, illustrating one of the fasteners. Fig. 3 is a section on line 3—3 of Fig. 2. Fig. 4 is a perspective of a fastener attached to the spring structure, the pad being omitted for illustrative purposes. Fig. 5 is a section of the fastener taken on line 5—5 of Fig. 2. Fig. 6 is a perspective of a stud-member of one of the fasteners. Fig. 7 is a perspective of the socket-member of one of the fasteners.

In the manufacture of mattresses in accordance with the invention, a spring center core comprising springs 10 and helicals 11, is assembled into a structure according to the size of the mattress desired, as well understood in the art.

The core constitutes a resilient center structure for the mattress. This structure usually consists

of coil-springs with marginal and longitudinal helicals or frame-members at the top and bottom by which the springs are held together in connected relation, it being understood that any suitable spring structure may be used. A fabricated boxing 12 is assembled around the sides and ends of the core, as well understood in the art. Next, top and bottom coverings, each consisting of suitable layers of padding material 13, an inner sheet, or lining 14 of fabric and an outer tick-member 15, are made up conforming to the size and shape of the mattress desired. The margins of the lining 14 and tick 15 are stitched together to enclose the padding material, so they will constitute preformed pads adapted to form resilient top and bottom coverings for the core.

The invention contemplates securing the padding 13, lining 14 and tick 15 together at spaced points, which may correspond to the points at which mattresses are usually tufted, by means of 20 fasteners which will compact or compress the padding material 13 at such points, before the top and bottom coverings are assembled with the core. These fasteners are of the stud-and-socket type. The stud-member comprises a head 18 for 25 engaging the outer face of the tick-member, a shank 18 which is adapted to extend through the covering, and provided with a pointed end 20 which is adapted to be forced through the pad to project from the inner side thereof. The 30 socket-member comprises a plate 21 provided with a hole 21^a through which the point 20 is adapted to pass, and resilient tongues 22 adapted to be engaged by the shoulder 20^a at the upper end of point 20 of the stud, to hold the stud-and-socket members in connected relation after the covering has been compressed between the head 19 and the plate 21. This socket-member is preferably cut and shaped from a single piece 35 of sheet or plate metal to form the plate 21 for 40 engaging the inner face of the lining 14 and the pair of resilient tongues 22, which are folded and extended inwardly from cuts in the margin of plate 21 and provided with semi-circular notches 23 at their inner ends to fit around the shank 45 18 of the stud above the shoulder 20^a at the upper end of the point 20 to secure the clip-member on the stud. Tongues 22 are resilient so they will be spread by the point 20 when the stud is forced through the pad and snap against the shank 50 above the stud to prevent separation of the stud and socket-members. In manufacturing mattresses in accordance with the present invention, the studs are passed through the coverings and secured in socket-members before the coverings 55

are assembled with the core and boxing of the mattress. These fasteners may be inserted through the pads at spaced points in a suitable press in which all of the socket-members for a covering are held in properly spaced relation on a bed and the studs held in a coacting press-member are simultaneously forced through the tick-member, padding and liner-sheet and holes 21^a in the socket-members of the fasteners until 5 the shoulders 20^b of ends 20 have passed through the notches 23 in resilient tongues 22. During 10 this operation the covering will be compressed by and between heads 19 of the studs and plates 21 of the socket-members and the members will be 15 secured against withdrawal from the covering.

Each fastener comprises a device for connecting it, after it has been secured in the covering, to the spring core. This device comprises a resilient tongue 26 struck from the plate 21 and 20 bent to form a hook 27 and a coacting tongue 28 also struck from plate 21 having a curved inner 25 end 29, and serving as a latch or snap for retaining a wire in the hook. The hook 27 and the curved end 29 of tongue 28, when pressed against any wire of the spring structure, will spring apart 30 and readily permit the wire to be forced into the hook and so that it will be secured in connected relation to the wire, as illustrated in Fig. 3.

In fabricating the mattress, the covering with 30 the assembled fasteners, is placed over the top of the core and the hooks 27 on the socket-members of the fasteners are successively connected to underlying wires of the spring core such, for example, as the top convolutions of 35 the springs or frame-members. In latching the hooks 27 to the spring core, one row of fasteners can be connected to the core while the unattached portion of the covering is folded upwardly, as illustrated in Fig. 1, and successive 40 rows of fasteners will then be connected to the core until all of the fasteners in that covering have been connected to the core. The top and bottom coverings are assembled and 45 connected to the core in the same manner so that the foregoing description is applicable to both.

When all of the fasteners on each covering have been connected to the spring structure, the margins of the covering and the boxing will 50 be stitched together to complete the fabrication of the mattress.

In the completed mattress, the studs will form depressions in the top and bottom pads to compact the padding in the coverings at the spaced 55 points and the fasteners will be secured to the spring core, so the coverings will be held on and against the top and bottom thereof. The reduced shanks 18 of the studs permit the padding to be further compressed under load and 60 to yield laterally when subjected to lateral pressure.

In the event that replacement of a covering is necessary, the studs of the fasteners can be separated from the socket-members by springing 65 apart the tongues 21, by means of a suitable pry or tool. This makes it possible to re-use the fasteners or remove a defective one.

The invention is not to be understood as restricted to the details set forth, since these may be modified within the scope of the appended claims, without departing from the spirit and scope of the invention. 5

Having thus described the invention, what I claim as new and desire to secure by Letters Patent is:

1. The combination in a mattress of a spring-center core, a pad extending over one of the faces of the core and comprising a ticking sheet, padding and a liner sheet, fasteners comprising studs extending through the covering at spaced points, compressor-heads on the studs and plate-members interlocked with the studs 15 so the pad will be compressed between the heads and said members and so that the pad will be independently tufted and self-retaining, and hooks on and extending inwardly from the plate-members and connected to parts of the spring- 20 core.

2. The combination in a mattress of a spring-center core, a pad extending over one of the faces of the core and comprising a ticking sheet, padding and a liner sheet, fasteners comprising 25 studs extending through the covering at spaced points, compressor-heads on the studs and members formed of plate metal and interlocked with the studs so the pad will be compressed between the heads and said members 30 and so that the pad will be tufted and self-retaining, and tongues extending inwardly from and integral with the plate-members and forming hooks and connected to parts of the spring- 35 core. 55

3. The combination in a mattress of a spring-center core, a pad extending over one of the faces of the core and comprising a ticking sheet, padding and a liner sheet, fasteners comprising 40 studs extending through the covering at spaced points, compressor-heads on the studs and members formed of plate metal and interlocked with the studs so the pad will be compressed between the heads and said members and so that the pad will be independently tufted 45 and self-retaining, tongues extending inwardly from the plate-members and forming hooks and connected to parts of the spring-core, and integral tongues integral with the plate-members for locking the studs and members together. 50

4. The combination in a mattress of a spring-center core, a pad extending over one of the faces of the core and comprising a ticking sheet, padding and a liner sheet, fasteners comprising 55 studs extending through the covering at spaced points, compressor-heads on the studs and members formed of plate metal interlocked with the studs so the pad will be compressed between the heads and said members and so that the pad will be tufted and self-retaining, 60 means extending inwardly from the plate-members and connected to parts of the spring-core, and integral resilient tongues on the plate-members and adapted to interlock with the studs for securing the fasteners to maintain the 65 pad compressed.

PETER C. BEDNAREK.
